HECTOR R. CARVETH, OF NIAGARA FALLS, NEW YORK, ASSIGNOR TO THE ROESSLER & HASSLACHER CHEMICAL CO., OF NEW YORK, N. Y., A CORPORATION OF NEW YORK.

PROCESS OF REGENERATING AIR.

1,111,055.

Specification of Letters Patent. Patented Sept. 22, 1914.

Application filed August 15, 1911. Serial No. 644,170.

To all whom it may concern:

Be it known that I, HECTOR R. CARVETH, a citizen of the United States, residing at Niagara Falls, in the county of Niagara and State of New York, have invented certain new and useful Improvements in the Process of Regenerating Air, of which the following is a full, clear, and exact description.

This invention relates to the regeneration of vitiated air by treating it with chemicals and with water vapor in such a way that its impurities are removed while its oxygen content is brought to a desired standard, and discloses a process which can effect such regeneration.

When air is taken into the lungs of a human being, there is absorbed from it a very considerable amount of oxygen; the exhaled air contains carbon dioxid and water vapor. In many cases it would be of great value if the air could be restored to the condition in which it was originally, so far as its freedom from carbon dioxid, and its normal content of oxygen and water vapor are concerned. This so-called regeneration of air is of the greatest value where it is necessary for a person to work in an atmosphere which will not support life; for in such cases all that is required is that the person carry with him an apparatus into which he may breathe the exhaled air and from which he can continuously withdraw air practically pure after it had been so treated as to effect its regeneration. Apparatus of this kind is in use among firemen, mine rescue squads and divers. Of the parts essential for supplying air, the apparatus may comprise the following (a) a helmet which protects the head and which also acts as an air reservoir (b) a tube designed to carry exhaled air from the helmet to the regeneration chamber (c) a chamber where the air is regenerated (d) a tube to carry the regenerated air back to the helmet. These four parts form a closed air circuit which when properly designed can support the life of the operator for a long time even when no fresh air is added to the circuit from outside.

This invention relates to the process of treating the air with a substance or mixture of substances in the regeneration chamber of the closed circuit whereby the carbon dioxid is removed and oxygen added to bring its percentage back to approximately 19% or 20%. Belonging to the class of sub-

stances which by interaction with water can evolve oxygen and at the same time give a product which will absorb carbon dioxid, are the peroxids of the alkali and alkali earth metals, such as sodium peroxid, potassium peroxid, calcium peroxid, etc. The reactions enumerated above are the ones required in air regeneration; in the process now being described, a body such as an alkaline peroxid which can produce these reactions in the presence of water vapor and vitiated air or mixtures thereof, such as for example, a mixture of potassium and sodium peroxid, is used as "the regenerating agent."

I have found that the moisture in exhaled air in a closed circuit is insufficient in amount to produce by its reaction with sodium peroxid for example the oxygen evolution and the carbon dioxid absorption which are required to make the air suitable for continued respiration. The addition of more water will, however, produce the required result and it is necessary therefore to cause the air which has been dehydrated and partially regenerated, to absorb more moisture and react with a new mass of the regenerating substance; and by repeating the operations of humidifying the air and reacting the moisture with the chemical, the desired result is obtained.

One form of apparatus illustrating the application of the method is shown in Figures I and II, of which Fig. I is a plan view and Fig. II a cross section. Fig. III is a somewhat diagrammatic view showing the relationship of the apparatus of Figs. I and II to an apparatus complete in all its parts to effect regeneration, while Fig. IV is a rear view of the mask shown in Fig. III.

Like numbers refer to like parts in the several views.

To the regenerating chamber 1 is attached tube 2 through which the air passes into the chamber. There it meets a regenerating material 3 such as fused sodium peroxid (oxone), which is supplied in the form of lumps to compartment 4. This compartment 4 has walls 5, such as wire screen or perforated metal, which allow the passage of air while retaining the chemical in position. Some of the moisture is taken from the air when it reacts with the peroxid. The products of the reaction are gaseous oxygen and caustic soda which latter absorbs carbon dioxid from the air. If it is desired, this

section might be so designed that the air leaving it would be absolutely dry before it reached the next section 6, where by the lung pressure it is forced through a moistened sponge or cloth 7 herein called a "hydrating agent." Here the air gradually takes up more moisture before it passes into the next section 8, which also contains the dehydrating regenerating material, where to the air in the circuit oxygen is added and from which carbon dioxid is withdrawn.

By increasing the number of sections containing alternately hydrating and regenerating materials, it will be possible to remove the carbon dioxid as desired, to increase the oxygen up to and beyond the percentage found in normal air and to send back through outlet 10, the regenerated air supplied with the desired amount of moisture.

The reaction of water vapor and carbon dioxid upon the regenerating agent develops a great amount of heat; this raises the temperature of the regenerator chamber and thus gives to the air passing through this chamber a greater capacity for carrying water vapor when it is passing through the section containing the hydrating agent.

The relation of the regenerator to the other essential parts of an apparatus complete as described above is shown diagrammatically in Fig. III; Fig. IV presents a rear view of the mask only. The mask A is fitted to the head by means of an air tight cushion, and is so designed as to leave an air space between the mask and the face. Exhaled air is blown through mouthpiece B into tube C which passes through the mask to regenerating chamber D, details of which construction have already been explained in Figs. I and II. After passing through D the course of the regenerated air is through E into an air reservoir F, then through tube G into the air space of the mask at H. Here the wearer of the mask receives his supply of regenerated air, inhaling it through his nose. The air has thus been forced in the one direction as described above and as indicated by the arrows in Fig. III. It is of course understood that all necessary connections and all parts of the apparatus are made air tight.

During the time it is being worn, this apparatus in connection with the lungs of the wearer constitutes a true closed circuit so far as the contained gases are concerned since the quantity and composition of the same are absolutely independent of the atmosphere surrounding the wearer.

As already stated above there is a development of heat when the carbon dioxid is absorbed and the water vapor reacts with the regenerating material. In my apparatus I plan not to waste all of this by radiation but rather to utilize it so as to raise the temperature of the air in the hydrator that it may

take up more water vapor there than it would if the air were colder. This increases the degree of reaction in the regenerator chambers and makes the apparatus more efficient.

I do not limit myself, further than the scope of the appended claims demand, to any stated number of sections of the apparatus nor to any particular form of apparatus; nor to a single regenerating chamber, for there may be conditions in which it may be advisable to operate several sections as different distinct units, nor to the use of any particular chemical or mixture of chemicals in the regenerating sections; nor to the use of pure water in the hydrating sections, since any solution or salt which gives off water vapor might also be used, nor to the use of wet sponge or cloth as the hydrating agents.

I wish to be understood that the term "regenerating agent" as used in the specification and annexed claims is intended to embrace a substance or a mixture of substances which by interaction with water evolves oxygen gas and furthermore gives or contains another product which absorbs carbon dioxid. And where I use the expression "alkali metals" in the claims, I mean to include as well the alkaline earth metals.

What I claim and desire to protect by Letters Patent is

1. The process of regenerating air consisting in passing the exhaled air in a closed circuit first over a regenerating agent, then over a hydrating agent and then over a regenerating agent.

2. The process of regenerating air consisting in passing the exhaled air in a closed circuit first over a regenerating agent, then over a hydrating agent, and then over other masses of the regenerating agent and the hydrating agent arranged alternately until the desired degree of regeneration is reached.

3. The process of regenerating air consisting in passing the exhaled air in a closed circuit first over a peroxid of an alkali metal, then over a hydrating agent and then over other masses of the peroxid of the alkali metal and the hydrating agent arranged alternately until the desired degree of regeneration is reached.

4. The process of regenerating air consisting in passing the exhaled air in a closed circuit first over a mixture of the peroxids of the alkali metals, then over a hydrating agent, and then over other masses of a mixture of the peroxids of the alkali metals and the hydrating agent arranged alternately until the desired degree of regeneration is reached.

5. The process of regenerating air consisting in passing the exhaled air in a closed circuit first over a mixture of a peroxid of an alkali metal and a peroxid of an alkali

earth metal, then over a hydrating agent, and then over other masses of said peroxid mixture and the hydrating agent arranged alternately until the desired degree of regeneration is reached.

6. In the process of regenerating air, passing the air in a closed circuit through a plurality of sections of a regeneration chamber, containing alternately a regenerating agent and a hydrating agent, so that the oxygen content of the air increases in each section containing the regenerating agent.

7. In the process of regenerating air, passing the air in a closed circuit through a plurality of sections of a regeneration chamber containing alternately a regenerating agent and a hydrating agent and maintaining said sections at a temperature above that of the surrounding atmosphere.

8. In the process of regenerating air, passing the air in a closed circuit through a plurality of sections of a regeneration chamber containing alternately an oxygen yielding

and carbon dioxid absorbing agents, and 25 a hydrating agent, so that the oxygen content of the air increases and the carbon dioxid content decreases in each section containing the first named agents and the water vapor content of the air increases in each 30 section containing the hydrating agent.

9. In the process of regenerating air, passing the air in a closed circuit through a plurality of sections of a regeneration chamber containing alternately a reagent which 35 evolves heat while regenerating air, and a hydrating agent, so that the air is regenerated and heated and then subjected to the action of the hydrating agent at an elevated temperature.

In testimony whereof I have signed this specification in the presence of two subscribing witnesses.

HECTOR R. CARVETH.
